UNITED STATES PATENT OFFICE.

OTTO P. SWARTZ, OF MOUNT PLEASANT, PENNSYLVANIA.

INSULATOR.

1,186,862.

Specification of Letters Patent. Patented June 13, 1916.

Application filed September 9, 1915. Serial No. 49,703.

To all whom it may concern:

Be it known that I, OTTO P. SWARTZ, a citizen of the United States, and resident of Mount Pleasant, in the county of Westmoreland and State of Pennsylvania, have invented certain new and useful Improvements in Insulators, of which the following is a specification.

This invention relates to insulators used 10 in supporting electric wires such as telephone, light and power transmission wires, trolley wires, and similar conductors of electricity.

One object of my invention is to provide 15 an insulator of improved construction having novel means whereby the wire conductors are prevented from being grounded by water and moisture.

Another object of the invention is to provide 20 an insulator having improved means for shedding water from the insulator and preventing a ground being formed by water on the insulator with the wire or conductor supported on the insulator.

Still further objects of the invention will 25 become apparent hereinafter as will be more fully described in the detailed description and particularly pointed out in the appended claim.

Referring now to the drawings forming 30 part of this specification, Figure 1 is a side elevation showing the upper end of an insulator constructed in accordance with my invention. Fig. 2 is a sectional elevation of 35 the insulator shown in Fig. 1, the section being taken on the line II-II of Fig. 3. Fig. 3 is a top plan showing the upper end of the insulator illustrated in Figs. 1 and 2. Fig. 4 is an inverted plan showing the lower 40 end of the insulator of Figs. 1, 2 and 3.

In the accompanying drawings the numeral 2 designates the annular outer body portion of the insulator, having a curved upwardly and outwardly flaring petticoat 3 45 on its upper end 4 and a similarly curved outwardly and downwardly flared petticoat 5 on its lower end 6. The outer or peripheral surface of the body portion 2 at about the middle of its length is provided with an 50 encircling groove 7 in which the wire or conductor is secured when the insulator is in use. The upstanding petticoat 3 forms a recess, in the top or upper end of the body portion 2 and the recess formed in the lower 55 end 6 forms a drip 17, or in effect a double

petticoat on the lower end of this portion of the insulator. The annular body portion 2 of the insulator is integrally joined to the cylindrical inner body portion 8 by a plurality of radial ribs 9, three of these ribs 55 being employed in the insulator shown, (although obviously a greater number should and will be used with larger insulators and a less number may be used with smaller sizes of the insulators). The use of 60 the radial ribs 9 provides openings 10, 10 10 between the inner surface 11 of the body portion 2 and adjoining outer surface 12 of the inner body portion 8 through which water is drained from the petticoat 3 and is 70 prevented from coming in contact with the lag screw 13 used in fastening the insulator to a support. The insulator is formed of glass, porcelain, glazed clay or other suitable material. The axial opening or hole 14 75 in the inner body portion 8 is provided for the lag screw, bolt or equivalent fastening means 13 employed in securing the insulator to the cross arm or other support to which the insulator is applied for use. The central body portion 8 of the insulator and the radial ribs 9 are somewhat longer than the overall length of the outer portion 2, the extra length being added at the upper end 80 of the insulator and the surface 15 of the upper end is flat to provide a bearing surface for the insulator in attaching it to a support. The lower end surface 16 is recessed to receive the head of the lag screw or fastening 13 or a washer on this end of 90 the lag screw and the annular projection defining the side wall of this recess is beveled to a sharp edge to form a drip 17 which prevents water on the outer surface 12 of the inner body portion 8 from coming into 95 contact with the metallic fastening 13.

From the above description it will be readily understood that water on the upper end of the body portion 2 of the insulator will flow downwardly through the vertical 100 openings 10 and off the drip or petticoat 7 without contact or liability of contact with the inner body portion 8 and fastening 13 and that water on the inner body portion 8 will flow downwardly through the vertical 105 openings 10 and drain off the drip 17 without contact with the fastening 13 so that the liability of grounding or loss of current through the insulator when wet is lessened and reduced to a minimum. The use of the 110

- petticoats on the upper and lower ends of the outer body portion 2 of the insulator prevents water on the insulator from coming into contact with and grounding a bare wire supported by the insulator or with an insulated wire when an insulated wire is fastened to the insulator so as to prevent corrosion or rotting of the insulation on such wire.
- 10 The recesses provided in the lower ends of the inner and outer portions of the body result in the formation of spaced annular drip edges which are concentric and in the same plane, thereby readily shedding moisture and preventing the same from collecting at the lower end of the insulator.
- 15 The advantages of my invention will be apparent to those skilled in the art. The insulator is simple and is easily and cheaply
- made while by its use the effectiveness of 20 such appliances is materially increased.

I claim:—

An insulator consisting of a cylindrical body comprising inner and outer spaced portions and longitudinal connecting ribs, the 25 inner portion and ribs projecting above the outer portion, and the inner portion having an axial opening and its lower end recessed, and the outer portion having its ends exteriorly and outwardly flared in opposite 30 directions and having annular recesses in its extremities, the recesses in the lower ends of the spaced portions forming annular concentric drip edges in the same plane.

In testimony whereof I have hereunto set 35 my hand.

OTTO P. SWARTZ.
